Primary Examiner — John R Yeh

(57) **CLAIM**

The ornamental design for a mop head, as shown and described.

DESCRIPTION

FIG. 1 is a front, top and right-side perspective view of the mop head showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a back, bottom and left-side perspective view thereof;

FIG. 9 is another perspective view thereof shown in an exploded condition; and,

FIG. 10 is another perspective view thereof shown in an exploded condition.

The broken lines throughout the drawing figures depict portions of the mop head that form no part of the claimed design.

1 Claim, 10 Drawing Sheets
